UNITED STATES PATENT OFFICE.

GRIFFITH JOHN, OF YONKERS, NEW YORK, ASSIGNOR TO OTIS ELEVATOR COMPANY,
OF JERSEY CITY, NEW JERSEY, A CORPORATION OF NEW JERSEY.

ESCALATOR-BRAKE.

1,200,502.

Specification of Letters Patent. Patented Oct. 10, 1916.

Application filed August 25, 1913. Serial No. 786,575.

To all whom it may concern:

Be it known that I, GRIFFITH JOHN, a subject of the King of Great Britain, residing in Yonkers, in the county of Westchester and State of New York, have invented a new and useful Improvement in Escalator-Brakes, of which the following is a specification.

My invention relates to safety brake apparatus for passenger type of conveyers, commonly called escalators, and more particularly for reversible type of escalators, and has for one of its objects, the provision of automatically operative means for effecting the retardation of the escalator, when the latter attains an undue rate of speed.

Another object of the invention is to provide a mechanical safety brake in conjunction with a power unit having a brake associated therewith, and means associated with the safety brake apparatus operable automatically upon excessive speed of the escalator to effect the retardation of the latter, and simultaneously to disconnect the driving unit from its source of power supply, whereby the primary brake will operate to retard the driving unit simultaneously with the application of the safety brake.

As before stated herein, my invention is applicable more particularly to a reversible type of escalator, for the reason that in an escalator operable only in an ascending direction, it is necessary to provide only a non-returnable brake device such as a roller brake or ratchet, so that in case of a runaway, such as would result in case of the driving mechanism giving out for example, the escalator cannot run down, but for a reversible escalator, which I will say for example is descending with a heavy load, and in this instance, if the driving mechanism gives out, the application of the roller brake or ratchet will cause the escalator to come to a sudden stop, which would cause the passengers to be thrown forward and downward, and might result in a very serious accident, and to this end I provide automatically operative means operable to effect a gradual retardation of the escalator and without danger of injury to the passengers.

Referring now to the drawings, Figure 1 shows in elevation, a general arrangement of an escalator, and driving mechanism, etc., therefor, with my invention applied

thereto, also an electrical controlling device therefor, shown in a modified form; Fig. 2 shows in detail, an enlarged view of the safety brake apparatus and automatically operative mechanism associated therewith; Fig. 3 shows a plan view of Fig. 2; Fig. 4, shows in detail a view of a centrifugal governor, used in conjunction with my invention.

The apparatus shown in Fig. 1 comprising the escalator proper, will be described only in general, the details of construction and arrangement of parts being fully shown and described in the patent to C. D. Seeger, No. 1,025,316, issued May 7, 1912. In Fig. 1, a series of connected steps 1, are provided with rollers 2, adapted to travel on tracks 3. Links 4, associated with the steps on the upper run 5 and lower run 5' of the escalator mesh with sprocket wheels 6, fixed on a driving shaft 7, driven by a motor 8, through a double worm and gear connection 10. An electro-responsive brake apparatus 11, shown diagrammatically is of a well known type, and comprises a brake band 12 normally held applied to a brake pulley 13, by a spring 14, and released therefrom upon magnetization of an electromagnet 15. In addition to the latter brake, I provide an automatically operated differential safety brake 16, which comprises brake pulleys 17, which are located at both ends of the driving shaft 7, and are fixed thereon. Associated with each of the brake pulleys are brake levers 18 pivotally supported at 19 by brackets 20, which are suitably secured to framework 21, of the escalator. One of the ends of the brake bands 22, is fixed at a point 23 to the brake levers, and the other end at a point 24, these two points of connection on the lever 18 being such as to obtain a differential and powerful application of the brake bands, with the use of a small weight 43 adjustable on the lever 18. With the brake levers as shown in Fig. 2, the brake bands are released from the brake pulleys, and the levers under normal running conditions are held in this position by means of trip devices 25 and 25', fixed on a shaft 26. The trip devices are provided with a latch 27, which engages the ends 28 of their respective levers to keep the brake bands released from their respective pulleys.

A centrifugal governor 29 is fixed on a

shaft 30 with a sprocket wheel 31, and any suitable driving connection can be made therefor, either from the main driving shaft, through the medium of a sprocket and chain 5 connection, or from the links on the escalator steps as is shown in Fig. 2, which comprises a gear wheel 32, positioned to mesh with the links on the upper run of the escalator, the gear wheel in turn rotating the sprocket 10 wheel 33, which is on a shaft 34 therewith, the sprocket wheels 33 and 31 being connected by a sprocket chain 35. The centrifugal governor 29 is of a well known type and comprises a wheel 36, having a hub 37, and 15 arms 38, radiating therefrom. Weighted centrifugal arms 62 are journaled in the arms 38, and at the other extremity of each of the said weighted arms is engaged a rod 40, connecting it with the opposite weighted 20 arm at a point between the journal and the outer extremity 39, and each of the said rods are provided with springs 41. By this construction it is evident, the centrifugal impulse of each of the weighted arms is communicated to the other to make them act together. The governor is set to operate at a certain predetermined speed and when the arms fly outwardly the bosses 39 thereon 25 strike an arm 42, integral with the trip device 25, thereby knocking the latch 27 on the trip device out of engagement with the end of the brake levers, thereby allowing the brake band to be applied by the action of the weights 43, on the levers. The said 30 weights are adjustable on the levers by means of adjusting bolts 44. Upon operation of the trip device 25 it transmits motion through the shaft 26 to the trip device 25', thereby effecting the application of the brake 35 bands on both sides of the escalator simultaneously. An arm 45 integral with the trip device, effects the opening of a double pole knife switch 46, for a purpose hereinafter described.

45 The operation of the apparatus will now be described.

A direct current source of supply designated + and - is directed by means of a main line potential switch P, to a controller 50 box R and is directed therefrom in a manner to rotate the motor in a direction to cause the escalator to descend, for example. The potential switch is now closed by hand and is self holding, it having a winding 47 therefor, connected across the mains as follows: contacts 48 and 49, conductor 50, contact 51, contact 52, conductor 53, contact 54, switch 46, conductor 57, winding 47 to the minus line. The winding of the primary 55 brake electromagnet 15, is as follows: contacts 48 and 49, conductors 50 and 50', contacts 58 and 59, conductor 60, winding of the electromagnet 15, conductor 61, to the minus line. The primary brake magnet now 60 being energized will lift the brake, and the 65

motor will now operate to cause the escalator to descend. I will say now for example the escalator is heavily loaded, and the driving mechanism gives out, thereby causing the escalator to increase its speed above normal speed due to the heavy load thereon. The arms on the governor will now fly outwardly due to this increased speed, and will knock the latch on the trip device out of engagement with the brake lever, whereupon the weighted levers will effect the application of the brake bands instantly, and the escalator will be brought to a gradual stop. This operation of the trip device will cause the arm 45 thereon to open the knife switch 46, and thereby open circuit the winding of the potential switch, the said knife switch being connected in series with the potential switch winding. The potential switch will now open, thereby cutting off the current supply from the motor and primary brake and the latter will operate to retard the motor, which in this instance if allowed to continue its rotation might cause serious damage.

Although I have shown and described my invention applied to a conveyer of the step type together with a particular type of driving mechanism, I do not wish to be limited in the application of my invention to this particular type of conveyer or driving mechanism, and it is obvious that those skilled in the art may make various changes in the details of construction and arrangement of parts, without departing from the spirit and scope of my invention.

What I claim and desire to secure by Letters Patent of the United States is:

1. The combination with an electrical power unit having a main brake electrically associated therewith, a source of electrical power supply, a potential switch controlling circuits to the power unit and said main brake, an auxiliary brake, and governor-controlled means for controlling the operation of the switch and the auxiliary brake.

2. The combination with an electrical power unit, braking apparatus therefor, comprising a main electrically controlled brake and an auxiliary mechanical brake, a source of electrical power supply, a potential switch for controlling the operation of the power means and electrical brake, and governor-controlled means, operable to effect the opening of the switch and the application of the brakes simultaneously.

3. In safety apparatus, the combination with a main shaft, a countershaft, electric power means for driving the shafts, a source of electrical power supply, an electrically operated brake for the main shaft, an auxiliary brake for the countershaft, a potential switch for controlling the operation of the power means and electrical brake, a governor operatively connected with one of the shafts, and means controlled by the gov-

ernor, operable to effect the opening of the potential switch and the application of the auxiliary brake simultaneously.

4. In safety apparatus, the combination with a main shaft, a countershaft, electric power means for driving the shafts, a source of electrical supply, an electrically operated brake for the main shaft, an auxiliary mechanical brake for the countershaft, a potential switch for controlling the supply to the power means, an electrical circuit controlled by the potential switch for controlling the operation of the electro-magnetic brake, a governor operatively connected with one of the said shafts, and means controlled by the governor comprising a trip and switch, operable simultaneously to effect the opening of the potential switch and application of the auxiliary brake.
5. In safety apparatus, the combination with a main shaft, a countershaft, electric power means for driving the shafts, a source of electrical supply, an electrically operated brake for the main shaft, an auxiliary mechanical brake for the countershaft, a trip device for holding the latter brake released, a centrifugal governor for actuating the trip device, a normally closed switch adapted to be opened by the trip device, a potential switch having a self holding circuit including the last named switch, and a circuit controlled by the potential switch for controlling the operation of the electro-magnetic brake.
6. In safety apparatus, the combination with a main and countershafts driven by an electrical power unit, a source of electrical supply, an electrically operated brake for the main shaft, an auxiliary mechanical

brake for the countershaft, comprising a 40
brake pulley, a weighted lever, a brake band attached to the lever, a trip device engaging the lever normally to hold the brake band released, a centrifugal governor for actuating the trip device, a normally closed 45 switch adapted to be opened by the trip device, a potential switch having a self holding circuit including the last named switch, and a circuit controlled by the potential switch for controlling the operation of the 50 electro-magnetic brake.

7. In safety apparatus, the combination with a main and countershafts driven by electrical power means, a source of electrical supply, an electro-magnetic brake associated with the main shaft, an auxiliary brake for the countershaft comprising brake pulleys fixed at both ends thereof, a pair of pivoted levers, a pair of brake bands attached to the levers, a transverse rod, a pair of trip devices keyed to the rod and engaging the levers normally to hold the brake bands released, a centrifugal governor for actuating the trip device, a normally closed 55 switch adapted to be opened by one of the trip devices, a potential switch having a self holding circuit including the said last named switch, and a circuit controlled by the potential switch for controlling the 60 operation of the electro-magnetic brake. 70

In testimony whereof, I have signed my name to this specification in the presence of two subscribing witnesses.

GRIFFITH JOHN.
